METHOD AND MEANS FOR FORMING INTERNAL FLANGES ON TUBULAR BODIES

Application filed December 26, 1928. Serial No. 328,456.

My invention is an improvement in a method of and apparatus for flanging tubular articles and relates more particularly to a method and apparatus for forming a smooth internal annular flange on one or both ends of a tubular body.

Heretofore in forming flanges on tubular bodies, difficulty has been experienced in forming smooth continuous flanges, and so far as I am aware, it has not been possible heretofore to spin on such bodies smooth inwardly extending flanges which are free from irregularities of contour. It is common practice, I believe, to form outwardly extending annular flanges on tubular bodies by rotating the body and bending, by means of a flanging roller, a portion of the body against the side of a roller engaging the outer surface of the body. According to such a method, the flange so formed is not free from irregularities since the flange is not formed against a continuous or substantially continuous anvil.

It is one of the objects of my invention to form on one or both ends of a tubular body an internal flange free from irregularities of contour.

Another object of my invention resides in a method and apparatus for forming an internal flange on a tubular body against a substantially continuous anvil face by spinning the material of the flange toward and against the said continuous face.

Other objects and advantages of my invention will become more apparent as the following description of several embodiments thereof progresses, reference being made to the accompanying drawings in which like reference characters are employed to designate like parts throughout the same.

In the drawings—

Figure 1 is a front elevation of an apparatus embodying my invention and showing the means for feeding the flange forming roller toward or away from the work;

Figure 2 is a part plan view of the same showing the manner in which the flange forming roller engages the work and forms the flange against the anvil;

Figure 3 is a fragmentary elevation of an apparatus embodying the preferred form of my invention;

Figure 4 is a vertical section of the apparatus shown in Figure 3 but taken on line 4—4 of Fig. 1, some of the parts being shown in elevation;

Figure 5 is a fragmentary view of the apparatus shown in Figure 3, showing the jaws in retracted position for receiving or releasing the work;

Figure 6 is a plan view looking in the direction of line 6—6, Figure 3;

Figure 7 is a plan view looking in the direction of line 7—7, Figure 5;

Figure 8 is a partial section taken on line 8—8 of Figure 9, illustrating a second embodiment of my invention, the broken lines indicating the positions of certain of the parts when the jaws are retracted;

Figure 9 is a front elevation of the apparatus shown in Figure 8 with the hand-wheel removed;

Figure 10 is a bottom plan view looking in the direction of line 10—10, Figure 11; and

Figure 11 is a fragmentary view of the apparatus shown in Figure 8, showing the jaws in retracted position for receiving or releasing the work.

As illustrated in the drawings, my invention contemplates the use of a chuck or other work-holding means, the work gripping portions of which may be retracted to receive or permit removal of the work therefrom. It also contemplates the use of an anvil against which an internal annular flange may be formed on the work. By such means one end of the work may be flanged and the work subsequently may be removed from the chuck, reversed, and replaced on the chuck for flanging the other end.

Referring now more particularly to Figures 1 to 7 inclusive, which are illustrative of the preferred embodiment of my invention, the chuck body is indicated generally at 1. The chuck is driven or rotated by means of the driving pinion 2 keyed to a driven shaft 3. This pinion meshes with the teeth of the annular rack 4 formed on

the back of the chuck. Power is applied to the shaft 3 from a motor or the like (not shown) through suitable transmission means and a clutch (not shown) if desired. See 5 Figure 8.

The clutch body includes a hollow cylindrical portion having a front plate 5 and a plurality of radially sliding jaws 6 slideable between adjacent guides 7 bolted to 10 the chuck body as at 8.

In this embodiment of my invention a rod 9 is rigidly supported in the face plate 5 of the chuck body 1. The rod is threaded along a portion of its length as at 10 for 15 receiving the nut 11. A hand-wheel 12 is keyed to one end of the nut for turning the same on the threaded portion of the rod. The flanged end 13 of the nut is carried within the cap 14 and spaced therefrom by 20 suitable packing or washers 15. A polygonal sleeve 16 is slideable on the rod 9 and is secured to the cap by means of the bolts 17. Plates 18 having ears 19 for pivotally receiving one end of the respective links 20 25 are bolted to the respective flat sides of the polygonal sleeve 16 and the positioning projections 21 of the plates register with the depressions formed in the respective flat sides of the sleeve. Certain of the connecting links 20 are pivotally attached at their outer ends to the respective radially sliding jaws 6. Each of the jaws slides along the chuck face plate 5 between the guide plates 7.

In this embodiment of my invention I 30 have also provided means for forming a substantially continuous flat anvil face against which the flange on the work is formed. I have also provided means whereby the jaws and shoes carried thereby may 35 be retracted radially of the chuck face without interference from adjacent jaws or shoes.

The jaws 6 carry shoes 22 which are fixed with respect to the respective jaws when the 40 apparatus is in use, although these shoes may be removed for repair or substitution by shoes having an arc of another radius. Alternate jaws 23 slideable between guides 45 7 are provided with shoes 24 which are capable of relative movement with the respective jaws by which they are carried. This is illustrated in detail in Figures 4, 5, 6 and 7. The shoes 24 are normally seated against the respective alternate jaws 23 but 50 are capable of movement away from the jaws when the latter are retracted. Each of the jaws 23 is apertured at 25 to receive the spring 26 and the headed stem 27, a shoulder 28 extending into the aperture to provide a stop or abutment for one end of the spring 26, and against which the spring 55 may be compressed when the shoe 24 is moved away from the jaw. I have provided means in this embodiment of my invention for moving the shoes 24 outwardly

and substantially parallel to the axis of the chuck body when the jaws are retracted. Such means is illustrated in Figures 6 and 7 and includes the inclined or beveled abutting walls 29 and 30 of the adjacent shoes. 70

It will be seen then, that as the alternate jaws 6 and 23 are retracted along the chuck face by turning the hand-wheel, the said jaws will approach each other as they move radially toward the axis of the chuck. During this movement of the jaws the inclined walls 30 of the shoes 24 will slide upwardly of the inclined walls of the shoes 22 compressing the springs 26 as shown in Figure 7. The shoes 24 will overlap the anvil faces 80 31 of the adjacent shoes 22 when the jaws are fully retracted. In Figure 6 I have illustrated the relative positions of the shoes 22 and 24 when the jaws are extended to receive and grip the work, and it will be 85 noted that the anvil faces 31 and 32 of the respective shoes provide a flat, substantially continuous annular anvil against which the flange of the work is formed.

The operation of this embodiment of my 90 invention is as follows—

The operator first spins the hand-wheel 12 in a direction to cause the nut 11 and the sleeve 16 to travel along the threaded rod 9 away from the chuck face plate. In this manner the jaws 6 and 23 will be withdrawn or retracted radially along the chuck face and toward the axis of the chuck. The operator may now place the work W, preferably in the form of a tube, on the chuck, by 100 sliding the same axially over the chuck as shown in Fig. 4. The hand-wheel 12 is rotated or spun in the reverse direction, causing the nut and sleeve to travel along the threaded rod 9 toward the chuck plate 5. The links 20 are thus moved about their respective pivots and force the jaws radially outwardly of the face plate 5 to engage and grip the work as shown in Fig. 4. As the jaws move outwardly the compression of 110 the springs 26 will be exerted to retract the shoes 24 toward the respective jaws 23, permitting the inclined walls 29 and 30 of the adjacent shoes 22 and 24 to ride over one another until the movable shoes are seated against the jaws 23. When these shoes are thus seated, their anvil faces 32 will be in the same plane as the anvil faces 31 of the shoes 22, forming a flat substantially continuous annular anvil against which the 120 flange of the work is spun. This is clearly illustrated in Figs. 3 and 6. It will be noted that the inclined walls 30 and 29 of the adjacent shoes are in substantially abutting relation when the jaws are extended to grip the work.

Referring now more particularly to Figs. 1 and 2, in which I have illustrated the present preferred form of my invention, and assuming that it is desired to form an in- 130

wardly extending flange on the work, the operator applies power from a suitable source to rotate the chuck and the work gripped thereby. The flange roller carriage 5 C may be adjusted in a line substantially parallel to the axis of the chuck along the guides G, by suitable means, and may be adjusted transversely of the work by means of the crank K and the screw S as shown in Fig. 2.

As the chuck and work are rotated, the flanging roller 49 is slowly fed to the right in Fig. 2, where it will engage the portion F of the work and form or spin it toward and against the alined anvil faces 31 and 32 of the respective shoes. Since the anvil faces are arranged in substantially abutting end to end relation and since the adjacent walls of the shoes are disposed at an angle to the radii of the chuck, they constitute a substantially continuous flat, annular anvil face against which the flange F is spun. In this manner an even, true annular flange is formed extending inwardly toward the axis of the work, and which will be found to be free of irregularities of contour such as humps or wavy portions.

When it is desired to flange both ends of the work, the work may be released again by rotating the hand-wheel and retracting the jaws, and reversed on the chuck, where by repeating the operation above described a similar flange may be formed on the other end of the work.

To release the work from the chuck, as in reversing it to form a similar flange on its other end, or to remove the work entirely, the operator rotates the hand-wheel 12 in the opposite direction retracting the nut 11 and the sleeve 16 to the right in Figure 4. Such movement will, through the links 20, retract the jaws radially toward the chuck axis, causing the inclined surfaces 30 of the shoes 24 to move outwardly along the inclined surfaces of the shoes 22 and against the compression of the springs 26. In this manner the jaws may all be retracted toward the axis of the chuck along their respective radii without interference from the close fitting edges of the shoes, and for a sufficient distance to permit removal of the work which has been flanged on both ends.

In the second embodiment of my invention shown in Figures 8 to 11 inclusive, I have provided means for sliding certain of the jaws radially along the chuck face at greater speeds than certain other of the jaws, the purpose of which will be more fully described hereinafter. This means includes a rod 33 rotatably mounted in the plate face 5 of the chuck and secured against axial movement by the collars 34 and 35. The collar 35 is preferably formed on the rod 33, while the collar 34 is removable and is secured in place by the set-screw 36. The

rod 33 is provided along a portion of its length with threads 37 of relatively high pitch and is also provided along another portion of its length with threads 38 of relatively low pitch. A hand-wheel 39 is keyed at 40 to the outer end of the rod for turning the same.

Nuts 41 and 42 are threaded internally and travel along the threaded portions 37 and 38 respectively of the rod when the latter is rotated. Pivotally connected to the nut 41 at one end are a plurality of links 43 having their respective other ends pivotally connected to respective alternate jaws 44 of the chuck, while a plurality of links 45 are pivotally connected at one end to the nut 42 and at the other end to the alternate jaws 46. Thus it will be seen that by turning the hand-wheel in one direction the jaws 44 will be retracted at a greater speed than the jaws 46, due to the difference in the pitches of the threads 37 and 38. I have illustrated the respective pitches of the threads 37 as being approximately double the pitch of the threads 38, enabling the jaws 44 to be retracted twice as fast as the jaws 46. This is clearly illustrated in Figure 8 where I have shown the relative positions of the various parts in full lines indicating the jaws in extended position for securely holding the work and in dotted lines illustrating the jaws in retracted position for receiving or releasing the work.

Each of the jaws is provided with a segmental face plate 47 of desirable material upon which the flange on the work is formed. Each face plate is provided with an anvil face 48 against which the flange is formed as will be more fully described hereinafter. Referring more particularly to Figure 9 it will be seen that when the jaws are extended along the face of the chuck to engage and grip the work, the anvil faces 48 of all the jaws will form a substantially continuous annular anvil. When the jaws are retracted, the anvil faces 48 of the jaws 44 will be offset circumferentially but in substantially the same radial plane with respect to the faces 48 of the jaws 46, since in retracting all the jaws the former will be withdrawn approximately twice as far as the latter, as shown in Figure 11. I have provided such means for retracting certain of the jaws to a greater retracted position than certain others to permit free radial movement of the jaws 46 toward the axis of the chuck and without interference from the jaws 44, and to provide sufficient clearance for removing the work.

It will also be noted from Figures 9 and 11 that the ends of the anvil faces on the jaws 46 converge toward the axis of the chuck, while the ends of the anvil faces on the jaws 44 converge away from the axis of the chuck. It is to be understood, how-

ever, that I may reverse the convergence of the ends of the respective anvil faces on the respective jaws if desired without departing from the spirit of my invention or the scope of the claims. By means of the construction just described it will be noted that the adjacent end walls of adjacent anvil faces are maintained in substantially abutting relation regardless of the position of the jaws in use, there being only sufficient space between the said adjacent end walls to permit clearance when the jaws are moved relatively to one another.

In use, the invention, as illustrated in Figures 8 to 11 inclusive, operates as follows:

The operator first spins the hand-wheel 39 in a direction to retract the alternate series of jaws 44 and 46 toward the axis of the chuck 1. In so doing the nuts 41 and 42 travel away from each other along the respective threaded portions 37 and 38 of the rod 33, as illustrated by dotted lines in Figure 8. Since the threads 37 are of greater and opposite pitch to that of the threads 38, the nut 41 will travel a greater distance along the rod 33 than the nut 42 for a given number of revolutions of the hand-wheel. Consequently the jaws 44 connected through the links 43 to the nut 41 will be retracted for a greater distance than will the jaws 46, as indicated in the figure in dotted lines, and the abutting inclined edges of the adjacent shoes 47, when the jaws are extended, will gradually ride over one another as the jaws move inwardly to prevent interference with the radial movement of the jaws. The operator may now place the work W on the chuck by sliding the same axially over the chuck as indicated in Figure 8. The hand-wheel 39 is spun in the reverse direction causing the nuts 41 and 42 to travel along the rod toward each other until the jaws 44 and 46 engage and securely grip the work W. When the jaws are in this position it will be noted that the shoes 47 also grip the work presenting their anvil faces 48 in the form of a substantially continuous anvil, to that portion of the work which is to be formed into a flange.

Referring now more particularly to Figs. 1 and 2 for the purpose of describing the operation of the invention shown in Figs. 8 to 11 inclusive, and assuming the work is in place on the chuck for flanging, the operator applies power from a suitable source, including a transmission device and a clutch, if desired, and through the driven shaft and pinion to rotate the chuck. The operator now adjusts the flanging roller 49, which is freely rotatable on its shaft, to engage the work. The roller carriage C may be adjusted in a line parallel to the axis of the chuck along the guides G, while by turning the screw S by means of the crank K,

the roller may be fed transversely of the work as indicated in dotted lines in Figure 2. As the chuck and work are rotated and the roller 49 is fed slowly to the right in Figure 2, it will engage the portion F of the work and form or spin it toward and against the anvil faces 48 of the shoes. Since the anvil faces are arranged in substantially abutting end to end relation, and since the adjacent walls of the shoes are disposed at an angle to the radii of the chuck, they constitute a substantially continuous flat annular anvil face against which the flange F is spun. In this manner an even, true annular flange is formed extending inwardly toward the axis of the work, and it will be found to be free of irregularities such as humps or wavy portions as are encountered in similar articles flanged in other ways.

When it is desired to flange both ends of the work, the work may be released again and reversed on the chuck where by repeating the operation above described a similar flange may be formed on the other end of the work.

According to my invention, the method of forming an inwardly extending annular flange on a tubular body, may be described as follows:

The work is placed on the chuck in the manner already described and is securely held thereon by adjusting the hand-wheel. Power is applied to rotate the chuck and the work and the operator feeds the flange forming roller toward the overhanging portion F of the tubular body W. The nose of the roller presents a blunt rounded surface and engages the portion F at a point opposite the outer peripheral edges of the respective shoes. As the operator continues to feed the carriage C transversely of the work axis, the nose of the roller will bend or spin the material of the portion F inwardly and against the flat substantially continuous annular anvil hereinbefore described in connection with the illustrated embodiments of my invention.

In carrying out this method of forming an annular, internal flange on a tubular body, I prefer to spin the flange portion of the material of the said body from a point opposite the outer peripheral edges of the respective shoes toward the peripheral outer edge of the tubular body, although it is to be understood that the flange may be formed by spinning the flange portion of the material from its outer peripheral edge toward the point opposite the outer peripheral edges of the shoes.

By means of my invention an internal flange may be formed on each end of the tubular body by first forming an internal flange on one end and reversing the body on the chuck and forming an internal flange

on the opposite end of the tubular body, and it is to be understood that the method above described contemplates forming an internal annular flange on one or both ends of the tubular body.

5 Various changes may be made in the details of construction and arrangement of parts of my invention without departing from the spirit of the invention or the scope of the subjoined claims.

I claim:

1. The method of forming an internal flange on a tubular body, which consists in rotating the body on a support and simultaneously spinning a portion of the body near one of its peripheral edges against an anvil, and then retracting the anvil to remove the tubular body from the support.

2. The method of forming internal flanges on a tubular body, which consists in rotating the body on a support and simultaneously spinning a portion of the body near one of its peripheral edges against an anvil, and then retracting the anvil to remove the tubular body from the support, and then reversing the body on the support and similarly forming an internal flange on the other end of the tubular body.

3. An apparatus for forming internal flanges on tubular bodies, including a rotatable support for the tubular body, radially movable jaws carried by the support for gripping the tubular body, anvils carried by the jaws, said anvils underlying the portion of the tubular body to be formed into a flange, and a flange forming roller engageable with the said flange portion of the body for spinning the flange portion against the anvils.

4. An apparatus for forming internal flanges on tubular bodies, including a rotatable support for the tubular body, radially movable jaws for gripping the body, anvils carried by the jaws and having a portion of the tubular body overlying the said anvils, and a blunt-nosed flanging roller engageable with the said overlying portion of the tubular body to spin the same progressively toward and against the anvils.

5. An apparatus for forming internal flanges on tubular bodies, including a rotatable support for the tubular body, radially movable jaws for gripping the body, anvils carried by the jaws, and arranged to provide a substantially continuous annular anvil face when the jaws are in position to grip the tubular body, and means for simultaneously moving said jaws to grip or release said tubular body.

6. An apparatus for forming internal flanges on tubular bodies, including a rotatable support for the tubular body, radially movable jaws for gripping the body, anvils carried by the jaws and having a portion of the tubular body overlying the said anvils,

and a flanging roller engageable with the said overlying portion of the tubular body to spin the same toward and against the anvils, said anvils being retractile radially with the jaws to release the flanged body.

7. An apparatus for flanging a tubular body, including a rotatable support for the body, radially movable jaws for gripping the body on the support, an anvil against which the flange on the body is formed, and a blunt-nosed flanging roller engageable with a portion of the tubular body overlying the anvil for spinning the said overlying portion against the anvil.

8. An apparatus for flanging a tubular body, including a rotatable support for the body, radially movable jaws for gripping the body on the support, a substantially continuous anvil against which the flange on the body is formed, and a flanging roller engageable with a portion of the tubular body overlying the anvil for spinning the said overlying portion against the anvil, said anvil comprising a plurality of retractile anvil segments.

9. An apparatus for flanging a tubular body, including a rotatable support for the body, radially movable jaws for gripping the body on the support, an anvil against which the flange on the body is formed, and a flanging roller engageable with a portion of the tubular body overlying the anvil for spinning the said overlying portion against the anvil, said anvil comprising a plurality of anvil segments, some of which are movable relatively to the jaws in a plane substantially parallel to the axis of the rotatable support when the jaws are moved radially of the support.

10. An apparatus for flanging a tubular body, including a rotatable support for the body, radially movable jaws for gripping the body on the support, an anvil against which the flange on the body is formed, and a flanging roller engageable with a portion of the tubular body overlying the anvil for spinning the said overlying portion against the anvil, said anvil comprising a plurality of anvil segments movable with the respective jaws, to permit removal of the tubular body from the support.

11. An apparatus for flanging a tubular body, including a rotatable support for the body, radially movable jaws for gripping the body on the support, an anvil against which the flange on the body is formed, and a flanging roller engageable with a portion of the tubular body overlying the anvil for spinning the said overlying portion against the anvil, said anvil comprising a plurality of anvil segments movable with the respective jaws to permit removal of the tubular body from the support, certain of said anvil segments being

also relatively movable toward and away from certain of the respective jaws.

12. An apparatus for flanging a tubular body, including a rotatable support for the body, radially movable jaws for gripping the body on the support, an anvil against which the flange on the body is formed, and a flanging roller engageable with a portion of the tubular body overlying the anvil for spinning the said overlying portion against the anvil, said anvil comprising a plurality of anvil segments movable with the respective jaws to permit removal of the tubular body from the support, certain of said anvil segments and jaws being movable as a unit at a greater speed than certain other of the segments and jaws.

13. An apparatus for flanging a tubular body, including a rotatable support for the body, radially movable jaws for gripping the body on the support, an anvil against which the flange on the body is formed, and a flanging roller engageable with a portion of the tubular body overlying the anvil for spinning the said overlying portion against the anvil, said anvil comprising a plurality of anvil segments movable with the respective jaws to permit removal of the tubular body from the support, certain of said anvil segments and jaws being movable as a unit at a greater speed than certain other of the segments and jaws, and means for simultaneously retracting certain of the jaws and anvil segments at a greater speed than certain other of the segments and jaws.

14. An apparatus for flanging a tubular body, including a rotatable chuck, means to rotate the chuck, jaws movable radially of the chuck to grip the tubular body thereon, a segmental anvil against which the flange on the body is formed, and a flanging roller engageable with a portion of the tubular body overlying the anvil for spinning the said overlying portion against the anvil, said segmental anvil presenting a substantially continuous flat anvil face to the overlying portion of the body when the latter is gripped by the jaws, the abutting walls of the adjacent segments being inclined to permit certain of the anvil segments to be moved out of the plane of certain other of the segments when it is desired to remove the tubular body from the chuck.

15. An apparatus for flanging a tubular body, including a rotatable chuck, means to rotate the chuck, jaws movable radially of the chuck to grip the tubular body thereon, a segmental anvil against which the flange on the body is formed, and a flanging roller engageable with a portion of the tubular body overlying the anvil for spinning the said overlying portion against the anvil, said segmental anvil presenting a substantially continuous flat anvil face to the

overlying portion of the body when the latter is gripped by the jaws, the abutting walls of the adjacent segments being inclined to permit certain of the anvil segments to be moved out of the plane of certain other of the segments when it is desired to remove the tubular body from the chuck, and means for automatically returning the movable segments to the plane of the other segments when the jaws are moved to grip the tubular body.

In testimony whereof, I hereunto affix my signature, this 13th day of December, 1928.

CHARLES BOYE.
